UNITED STATES PATENT OFFICE.

ARCHIBALD C. HEAPHY, OF NEW YORK, N. Y.

CELLULAR PLASTIC CONSTRUCTION AND METHOD OF PRODUCING SAME.

Application filed May 15, 1918. Serial No. 234,685.

To all whom it may concern:

Be it known that I, ARCHIBALD C. HEAPHY, a citizen of the United States, residing at New York, in the county of New York and

5 State of New York, have invented certain new and useful Improvements in Cellular Plastic Construction and Methods of Producing Same, of which the following is a specification.

10 My present invention pertains to an improved cellular plastic construction and to the method of producing the same.

The invention has for its main object the production of a cellular plastic structure and 15 more specifically a reinforced structure. While applicable to various building or structural elements, such as walls, beams, girders, and the like, the invention is particularly adaptable to marine constructions, 20 such as barges, pontoons, dry-docks and the like, and more particularly the hull construction of ships, either as a hull proper or as a sheathing therefor.

The invention is illustrated, in so far as is 25 necessary to an understanding thereof, in the annexed drawings, wherein:

Fig. 1 is an elevation of a mold wherein, at the left, the cells and reinforcing or tying elements are shown in position to receive the 30 plastic concrete or cement filling, while at the right the filling is in place;

Fig. 2 a vertical sectional view on the line II—II of Fig. 1, the forms being removed;

Fig. 3 a perspective view of one of the 35 cells employed in the structure; and

Fig. 4 a sectional view of the hull of the ship having that portion thereof which is below the water line formed from layers of such cellular construction, the various layers 40 having different specific gravities for an equal cubical area.

It will, of course, be understood that the drawings are more or less diagrammatic and that in so far as the spirit of the invention 45 is concerned that the structure, or more specifically, the structural elements thereof, may be modified and arranged to suit the particular requirements of any specific case or embodiment. It is also to be understood

50 that the terms "plastic material" or "concrete," hereinafter employed, are to be treat-

ed as the equivalents of any suitable plastic cement or mixture which may be found suitable for the purposes of the present invention.

55

Referring to the drawings, it will be seen that I employ in the structure a series of hollow chambers, which are made of metal or other suitable substance, and are air-tight. The chambers or cells 1 will be of varying 60 shapes in cross-section, as shown in Fig. 1, so that when positioned within the form or mold 2 there will be left in and about them a series of inter-connected or communicating channels or spaces, such channels being denoted by 3 at the left of Fig. 1. The cells or chambers 1 will preferably be angular in cross-section, and such shapes will be provided as will sufficiently fill the mold to the desired or necessary extent to produce 65 the requisite space for the plastic material, denoted by 4. Where the ultimate structure is to be light for a given cubical area, the cells will be relatively large, and, conversely, where the structure is to be heavy the 70 cells will be smaller or spaced apart to a greater extent.

To the end walls of each cell or chamber there will be secured, as for instance, by electric welding, a plurality of laterally projecting arms 5, having out-turned pronged ends 6. Where these arms cross or overlap they will, by preference, be bolted or otherwise secured together forming, in effect, a spider frame construction which, with the 85 out-turned ends, form an anchorage for the plastic material which entirely surrounds and embeds the cells and braces upon being poured, into the surrounding mold. The inter-connection of the cells and the pronged 90 ends resist the upward pressure of the cells during the process of pouring the plastic material and until the same has acquired its set. When the plastic material becomes set and hard there is produced a strong reinforced structure having a series of voids 95 therein which are water and air-tight and which is at once light as compared to a solid structure of the same size and plastic material.

100 By employing cells of angular formation, as, for instance, hexagonal main cells with

triangular and quadrilateral filling cells, the structure is of substantially even formation throughout. The angular formation of the cells, moreover, materially adds to the strength of the structure, though it is to be understood that I do not desire to confine myself to such shapes.

10 Columns and girders may be produced by employing molds or forms of the required height or length and such members thus built up will be at once light and strong. Under the arrangement of cells shown in Figs. 1 and 2, the voids will approximate 75% of the total cubical content.

15 As above noted, the invention lends itself to use in marine structures, and in Fig. 4 there is illustrated a ship provided with a hull having a structure, such as is above described, embodied therein.

20 The hull may be said to be laminated, the various layers having different specific gravities for the same cubical area. Thus the outer layer or sheathing 7 may be formed of concrete or solid reinforced concrete, the 25 next layer 8 being of a cellular construction, as above described, the cells or voids being small as compared to the next adjacent layer 9, while the innermost layer 10 has cells or voids of still larger size. There is thus produced a hull, the various laminae of which are of different specific gravities for a given cubical area, a feature of advantage against collision with floating mines, and also against torpedo attacks. When subjected to 30 the impact of explosion the outer skin or layer 7 of solid concrete resists the same, but in the event that the force of the explosion is severe, the solid layer will disintegrate and drop away, thus relieving the ship of 40 its dead weight and rendering the same more buoyant.

Having thus described my invention, what I claim as new and desire to secure by Letters Patent is:—

45 1. That method of producing reinforced plastic structures which consists in placing a plurality of rigid, hollow, water and air tight cells within a mold and spacing the same apart, and thereafter pouring plastic material into the spaces or channels left between and about such cells and the mold.

50 2. That method of producing a light reinforced plastic structure, which consists in placing a plurality of rigid inter-connected and spaced water and air tight cells within a mold and thereafter pouring plastic material into the spaces or channels left between and about such cells and the mold.

55 3. A reinforced plastic structure comprising, in combination, a plurality of rigid air-tight metallic cells, said cells being spaced away from each other; and a body of plastic material filling the spaces or channels between such cells.

4. A reinforced plastic structure comprising- 65 in, in combination, a plurality of cells, inter-connecting and spacing spiders fixedly secured to said cells; and a body of plastic material filling the spaces or channels between said cells and likewise embedding the 70 spiders.

5. A reinforced plastic structure comprising- 75 a series of air-tight metallic cells, angular in cross-section; a series of members secured thereto and extending outwardly therefrom; means for securing the ends of adjacent members to each other and thereby holding the cells in spaced relation; and a body of plastic material filling the spaces between the cells and embracing the spacing 80 members.

6. A reinforced plastic structure comprising- 85 a series of rigid air-tight cells; spider frames fixed to and connecting and spacing said cells; and a body of plastic material filling the spaces between the cells and embracing the spider frames.

7. A reinforced plastic structure comprising- 90 a series of metallic air-tight cells, angular in cross-section; arms secured to the ends of said cells and extending laterally therefrom; means connecting the ends of adjacent arms; and a filling of plastic material surrounding said cells and arms.

8. A ship the hull whereof is laminated, 95 the outermost layer being formed of solid plastic material and the next adjacent layer or stratum having a series of air-tight cells embedded in and surrounded by plastic material.

9. A ship the hull whereof is laminated, the various laminae being formed of plastic material possessing different specific gravities.

10. A ship the hull whereof is laminated, 105 said laminae being cellular in form and having different specific gravities.

11. A ship the hull whereof is laminated, the various laminae being formed of reinforced plastic material and being of different specific gravities, such difference being produced by voids or spaces therein of varying sizes.

12. A ship the hull whereof is produced from reinforced plastic material having air-tight voids therein, said material being laid on in laminae with the voids increasing in aggregate cubical area toward the inner portion of the hull.

13. A ship the inner portion of the skin 120 of the hull whereof is produced from reinforced concrete and an outer skin of plain concrete, said reinforced concrete having a plurality of air-tight voids therein.

14. A ship the hull whereof is produced 125 from reinforced concrete and an outer skin of plain concrete, said reinforced concrete having a plurality of air-tight voids there-

in, said voids increasing in aggregate cubical area toward the inner portion of the hull.

15. A flotative body comprising a plurality of air and water-tight cells surrounded and held in place by plastic material cast thereabout.

16. A flotative body comprising a plural-

ity of air and water-tight cells; a series of arms fixed to and extending outwardly therefrom; and a body of concrete cast about said cells and arms and embedding the same.

In testimony whereof I have signed my name to this specification.

ARCHIBALD C. HEAPHY.
